ABSTRACT

A device, especially adapted for incorporation in telephones and teleprinters in which a preset cassette is inserted into a reader and is operable to control pulse developing circuit means so as to emit a series of pulses programmed in conformity with the preset condition of the respective cassette.

**DEVICE FOR THE EMISSION OF
CURRENT-PULSE TRAINS PARTICULARLY BY
TELEPHONE AND TELEPRINTER
INSTALLATIONS**

The invention relates to a device for the emission of current-pulse trains particularly by telephone and teleprinter installations.

The object of the invention is a proposed device by which predetermined current-pulse trains can be emitted at will in a repetitive sequence. There is a requirement for such arrangements in telephone and teleprinter installations for establishing communication with particular, frequently called subscribers.

Such arrangements are already known which, however, operate by mechanical means. Thus, DT-A⁵ 1.278.529 describes an instrument operating by means of a number bank with pulsating slider contacts. Scanning is performed by a mechanical drive.

These devices are exposed to a particular degree of mechanical wear owing to the presence of numerous mechanical components which must be manufactured with a relatively high degree of precision and are consequently comparatively expensive. Relatively close tolerance limits are also necessary when manufacturing.

The basic problem of the invention is to provide a device of the aforementioned kind which can be produced at a comparatively low cost and is reliable in operation. In addition, the emitted pulse trains can be programmed by the actual user or subscriber, a considerable number of such preset pulse-train programs being made available without excessive expenditure of cost and space.

To solve this problem, the invention proposes the use of preset switching elements in power linkage with a scanning arrangement, the switching means being so designed and constructed that upon actuation of a release signal, pulse trains corresponding with the preset program are emitted.

The switching elements can be preset to a predetermined program by the actual user and are then connected when needed with the actual instrument, for instance, in unit block form. In the instrument, these switching elements then activate scanning means, in each case depending on the preset program, which, after the operation of a starting button or release fed in from the outside, cause the inserted program sequence to be suitably scanned so that a pulse train in accordance therewith is emitted which, for instance, corresponds with an assigned call number.

In one practical form of embodiment, the preprogrammable switching elements are in the form of cassettes equipped with a number of pins, adjustably positioned in the cassette. The operator (user) of the equipment thus has available a number of cassettes, it being possible to preset the signal pulse sequence to be emitted by suitable adjustment of the pins.

Advantageously, a neutral position of the pins is provided, when no switching is performed. These cassettes as a rule have a considerable number of pins so that it is possible to select a correspondingly large number of digits such as is required for subscriber trunk dialing, foreign and overseas calls and the like. In general, however, not all these digits or pins will be required, so that the unused pins can be set in this "blind" position.

Furthermore, another position of the pins is provided in which the emission of the pulse train is interrupted;

by repeated actuation of the release signal, the pulse train is again emitted at the interrupted point. This is the "spacing" position which is used to interrupt the selection sequence after completion of a preselected number.

The said pins can be in the form of longitudinally moveable contact sliders coacting with contact springs or blades, each of which closes a switching circuit in each longitudinally adjustable position. When a cassette is inserted with such preset pins, the contactor pins are thus moved in accordance with this programmed preset position, thereby compulsorily closing a switching circuit through their contact springs, which then, on arrival of the release signal pulse, triggers the appropriate pulse signal train.

The contact springs can in such case be forked with one arm slidable on a conductor bar or strip running in the direction of sliding and the other arm slidable over a number of switching strips running in a direction perpendicular to the preceding. In this especially practical embodiment, the first contact arm provides a continuous electrical contact with the conductor strip and the contact spring. Depending in each case on the position of the contact spring or its arm, preset by means of the pins and the contactor slides respectively, there is consequently a constrained connection between the second contact arm and exactly one of the transversely running switching strips or rails.

For the positional adjustment of the pins in their cassette, these pins are suitably toothed or notched to coact with a corresponding ratchet element in the bottom of the cassette. The bottom and lid of the cassette then form a casing enclosing the pins on all sides so that they are locked by the ratchets in their preset positions. If a pin requires to be reset in any other position, the lid of the cassette is removed. When the lid is replaced, the preset positions are immovably maintained.

The cassette lid is suitably arranged to run in drawer guides over the cassette bottom. This allows of easy resetting of the pins. To ensure that the contactor slides are able to resume their starting positions when the cassette is withdrawn, they are equipped with tabs pointing towards the top or bottom of the casing respectively, with which the slider of a cassette holder makes contact. This slider simultaneously serves as a guide for the cassettes placed on the holder. When the inserted cassettes are withdrawn, the slider makes contact with the aforesaid tabs and at the same time draws them into their starting positions.

For securing the cassettes in position relatively to the cassette slider, the cassette holder is equipped with pins matching corresponding holes in the cassettes and passing through the cassette lids and bottom elements. This simultaneously locates the cassette lid correctly with reference to the cassette bottom.

In order to ensure that the cassette holder can be inserted without skewing, a preferential form of embodiment of the object of the invention has not less than one pair of guides integral with the casing, which control the lateral movement of the cassette. This prevents any sideplay when the cassette or the cassette holder is inserted. Similarly, the preset programmed pins cannot deflect sideways. In a particular practical form of embodiment, two suitably spaced pairs of lateral guides, usually in the form of rollers, are provided.

For the same purpose, the slider guides may also be equipped with lateral guide pins or studs for the in-

serted cassette. These guide studs are provided with a guiding edge running longitudinally in the direction of insertion and acting as lateral guides.

It is further imperative to ensure that the device can be activated only when the cassette has been fully inserted into its final, end position. For this, in a preferential form of embodiment, mechanical and/or electrical interlocks are provided which ensure that the switching arrangement can be activated only after the cassette has been fully inserted into its final end position.

Such an interlocking element can suitably consist of a tumbler switch attached on the casing which is operated when the slider reaches its end position. Only when this slider has been actuated by the cassette will the scanning event with the preset numbers be able to commence.

Additionally, or alternatively, the mechanical interlock can be formed by a ratchet element integral with the casing which in the end position of the slider engages with a starter spring incorporated in the slider.

Finally, it is important that when inserted the contactor sliders reliably reach their respective longitudinal positions for switching so that presetting of intermediate positions is reliably prevented. For this purpose, spring elements can be associated with the contactor banks, by which spring elements ratchet pawl elements are caused to engage corresponding ratchet bars extending longitudinally along the backs of the contactor slides and by which the individual switching positions are predetermined.

In one practical form of embodiment, this spring element has the form of a multi-bladed leaf spring. The spring element is in this case a single spring leaf, suitably of metal, having a plurality of parallel slits along one side forming individual spring tongues, each assigned to and actuating a particular contactor slide.

Preferably the said ratchet element consists of a pressure-pin or set pin in contact with the spring element, actuating on a pawl of ball-shape working over the ratchet bar. This addition of a ball-shaped pawl element considerably reduces the amount of sliding friction between the elements.

The cassette lid is suitably arranged to work in drawer guides over the cassette bottom. This allows easy presetting of the contactor pins. In order that after withdrawal of any particular cassette the contactor slides thereof can resume their initial positions, they are equipped with tabs pointing upwards or downwards within the casing, with which the sliders of the cassette holder make contact. This slider likewise acts as a guide for the cassettes laid thereon. When the inserted cassettes are withdrawn, the slider makes contact with the aforesaid tabs and draws these likewise into their starting positions. If no pinned cassette is inserted in the cassette switching system, or if such a cassette has not been slid home against its end stop, the switching system is electronically held in the "permanent stop" position. To lock the position of the cassettes with reference to the cassette sliders, the cassette holder is equipped with pins entering corresponding holes in the cassettes and passing through both lid and bottom thereof. This simultaneously locks the cassette lids and bottoms in their correct position relatively to each other.

An important form of embodiment is further characterized by the provision of spring elements on the aforesaid pins, ending in contact points closing a circuit

in the switching system in the particular preset positions. This also dispenses with the use of contactor slides as separate elements of the arrangement.

These pins are consequently inserted in accordance with a predetermined code to varying depths in the scanning arrangement whereby current-pulse trains of varying length are then emitted. These consequently correspond generally with the preselected call numbers. Each pin suitably corresponds with one figure or digit of a particular call number. Through the spring elements respectively associated with these pins, corresponding switching points are activated.

It is preferable to make these springs fork-shaped, set with their arms in a slot of the pin, the fork ends being spherically swelled at the tip to form contact points. This allows of a construction with long spring paths and consequently full contact while the springs themselves are securely held in their slots.

For secure location of the springs in position on the pins, the spherical ends can be arranged to engage in perforations of the pins.

The stroke of the springs can be restricted by transverse pins fitted in the spherical tips.

For the same reason, short projections may be left beyond the spherical tips which in the inactive position bear against the sides of the aforesaid slots.

It is preferable for these slots to be provided at one end of the pin adjoining its end face. This frees the other end of the pin for the reception of further actuating means, while the spring can be housed inside the pin. Such actuating means may, for example, have the form of hammer heads to be actuated manually or by means of pliers or tweezers. A stop element can be provided in the vicinity of these actuating elements, whereby the depth of insertion of the pins can be regulated.

In one practical form of embodiment, the pins are arranged to be inserted in columns and rows, in the sockets of a guide plate on the back or spine of which a ratchet bar is attached for each socket, coacting with ratchet teeth in the form of notches on the particular pin. By this arrangement in columns and rows, or lines, a simple arrangement is obtained in the sense that each column of pins corresponds with a particular selectable call number. This array in parallel banks thus corresponds with the number of calling codes stored in the appliance.

Each bank of pins can thus be associated with a conductor plate carrying transverse and longitudinal contact strips. The number of transverse contacts then corresponds with the number of maximum digits from which a call number can be assembled, including any additional information such as intervals, etc.; and the number of longitudinal contacts corresponds with the number of banks of pins, for example, the number of calling sequences stored.

It is preferably to arrange a number of guide plates with their associated pins in a single cassette with sliding walls. This cassette is normally kept closed by these side walls so that unintentional disarrangement of the preset digital series is not possible.

The invention will now be described in more detail under reference to exemplary forms of embodiment thereof, from which further significant features of the invention will be made apparent:

FIG. 1 is a plan view of a telephone instrument with a device according to the invention;

FIG. 2 is a side elevation of the instrument according to FIG. 1;

FIG. 3 is a plan view of the bottom element of a cassette;

FIG. 4 is a section of the bottom element according to FIG. 3;

FIG. 5 is a side elevation of a contact pin;

FIG. 6 is a plan view of the pin according to FIG. 5;

FIG. 7 shows a cassette with inserted pins;

FIG. 8 shows a slider in plan view;

FIG. 9 is a side elevation of a slider in accordance with FIG. 8;

FIG. 10 shows a slider guide in plan view;

FIGS. 11a to 11f show different logical or electronic modules employed in the circuit arrangement according to FIG. 14;

FIGS. 12a and 12b show two pulse-train diagrams;

FIG. 13 shows an example of a selector pulse diagram;

FIGS. 14a and 14b show a complete circuit diagram;

FIG. 15 is a plan view of the lower contact bank;

FIG. 15A is an end view of FIG. 15;

FIGS. 15B to 15E are sectional views indicated by lines XV B to XV E on FIG. 15;

FIG. 16 is a plan view of the upper contact bank;

FIG. 16A is an end view of FIG. 16;

FIGS. 16B to 16G are sectional views indicated by lines XVI B to XVI E on FIG. 16;

FIG. 17 shows the contact slider;

FIG. 17A is an end view of FIG. 17;

FIG. 18 shows a contact spring to be inserted in the contact slider according to FIG. 17;

FIG. 19 is a side elevation of FIG. 10;

FIG. 20 is a top view of another form of embodiment of a cassette holder with lateral guiding means, in accordance with the view in FIG. 8 but with the cassette in place;

FIG. 21 is a section along the line XXI—XXI of FIG. 20 simultaneously showing further structural elements of the device;

FIG. 22 is a view in accordance with FIG. 15 of a modified form of embodiment showing the lower part of the corresponding contact bank;

FIG. 23 shows the upper part of the contact bank according to FIG. 22;

FIG. 24 shows, on a larger scale, the assembly of contact banks with spring and ratchet elements, in the form of embodiment according to FIGS. 20 to 23;

FIG. 25 is a plan view of a device according to the invention;

FIG. 26 is a side elevation of the device of FIG. 25;

FIG. 27 shows, diagrammatically, a detail in a cutout of FIG. 1;

FIG. 28 is a similar diagrammatic view of a direction perpendicular to that of FIG. 27; and

FIG. 29 is a magnified partial section of the arrangement according to FIG. 27.

BRIEF SUMMARY OF THE INVENTION

According to the present invention, two opposed sets of contact rails are provided, one set of contacts extending longitudinally and the other set extending at right angles thereto. Preset cassettes are adapted to be inserted in the device and include pins which can be adjusted longitudinally and which pins carry contacts for bridging between the contact banks so that each pin can make a predetermined connection between a re-

spective longitudinal rail and a selected one of the transverse rails.

The device is associated with a circuit arrangement which scans the contact rails and determines the points where the contact elements bridge between the rails and emits pulse trains in accordance with the bridged points. The pulse trains are consecutively emitted as the rails are scanned and, thereby, information can be transmitted by the train of pulses thus emitted.

DETAILED DESCRIPTION OF THE INVENTION

FIGS. 1 and 2 show an ordinary telephone handset 1 which is fitted on an appliance 2 comprising the principal features and elements of the device according to

the present invention. FIGS. 1 and 2 show a cassette holder 3 which is represented in more detail in FIGS. 8 and 9. This cassette holder is longitudinally slidable in the appliance 2 and both FIGS. 1 and 2 show the contact path with the activating and cancelling keys. The cancelling key is indicated at 83 and the activating key at 84.

FIGS. 3 and 4 show a cassette underpart 17 having transversely extending ratchet teeth 4. These represent the ten successive digits 0 to 9 as well as three special keys B, P and Z. FIG. 4 also shows dovetail guides for the cassette lid or upper part. In addition, two holes 5 are visible for coacting with corresponding pins 6 in the cassette holder.

FIGS. 5 and 6 show a programming pin 7, with teeth for coacting with the ratchet teeth 4 on the cassette.

FIG. 7 shows such a programmed cassette with a total of eighteen pins 7 inserted: Above in FIG. 7, the resulting preset "number" is shown in figures. FIG. 8 and 9 shows a cassette holder 3 with two pins 6. On the rear end of the cassette holder 3, inserted in the appliance 2, is an upwardly-pointing slider 8, coacting with studs 9 of sliding contactors 10, represented in FIG. 17. The slider 8 acts to return the sliding contactors 10.

FIG. 10 shows a slider guide 19 which is adapted to be screwed on the casing of the appliance 2, with laterally overriding guides 18 for the cassette holder 3.

FIGS. 15 to 15E show the under part 10a of the contactor magazine or contact store as a whole and in a number of cross sectional views. This contact store has a number of longitudinally extending guide slots 11 in which the sliding contactors 10 are longitudinally moveable.

These guide slots 11 have in their central part perforations 11a for the passage of the studs 9 on the sliding contactors 10.

At the rear end of the contact store extensions 12 of the guide slots 11 carry longitudinally extending conductor rails 12a, not further represented.

FIGS. 16 to 16E show the corresponding upper part 10b or lid of the contact store. Here again, guide slots 11 for the sliding contactors 10 are provided. In the rearward part transversely running switching rails 13a housed in receiving grooves 13 are similarly fitted.

The sliding contactors 10 shown in FIG. 17 have in addition to the stud 9, which goes in a slot 11a of FIG. 15, a circular socket 14 for correspondingly bent contact springs 14a, shown in FIG. 18. These contact springs have an upper contact arm 15 and a lower contact arm 16. The end of the upper contact arm 15 switches over the switching rails 13a lying in the receiving grooves 13, while the lower contact arm 16 slides

along the conductor rails $12a$ held in the extensions 12 (of the guide slots 11).

The electronic switching layout incorporated in the appliance 2 will now be more nearly described under reference to FIGS. 11 to 14. At the same time, the manner of action and interaction of the structural components already described will be explained. The principal components will firstly be described, under reference to FIGS 11a to 11f.

1. Digital Components

In this appliance, digital TTL switching circuits of series 74 are used. In these circuits, a distinction is made between the logical 1-level designated by H = high voltage at about $+3$ to $+5$ volts, and the logical 0-level designated by L = low voltage, at 0 volts. The switching scheme uses the following digital elements:

1.1. Reverser, or Inverter (FIG. 11a)

An H -level at the input produces an L -level at the output, or a positive pulse at the input produces a negative pulse at the output and vice versa.

1.2. NAND-Gate (FIG. 11b)

A NAND-Gate = Not and And Gate with two or more inputs and one output are positive And-connections with level-reversal at the output, i.e., the output has only one L -level; when all inputs have H , the inputs are interconnected and the circuit forms a reverser, or inverter.

1.3. NOR-GATE (FIG. 11c)

NOR-Gates with two inputs and one output are positive OR-circuits with level reversal at the output, i.e., the output has an L -level when one input has H ; or the output has H -level if both inputs have L (negative AND circuit with signal reversal).

1.4. Flip-flop FF (FIG. 11d)

Bistable multivibrator, so called Master-Slave flipflop is used for signal storage. The switching arrangements of the preparatory inputs J and K determine whether, for a positive synchro-pulse at the input T , the signal level at the outputs Q and $\bar{Q}$ changes. With a negative pulse at the reset input R , the output Q can be reset to L and the output $\bar{Q}$ set to H . The output Q always shows the complementary signal to the output level $\bar{Q}$.

1.5. Monostable Flipflop MF (FIG. 11a)

With a negative signal flank at the inputs $A1$ or $A2$ or a positive signal flank at the input B , the outputs Q and $\bar{Q}$ can produce a positive or a negative pulse train respectively, the length of the train being determined by the resistance R and the capacitance C .

1.6. Counting decade ZD and Decoder DC (FIG. 11f)

The counting decade ZD counts the positive pulses arriving at the A input ($A-JN = A$ input). At the outputs A , B , C and D , the counted pulse number is in "1248-Binary code" (BCD). At each 10th input pulse the counting decade is again zeroed. The decade can also be zeroed by a positive pulse through the inputs R_{01} and R_{02} . The corrected decoding circuit DC converts the binary decimal code into a "1 of 10 Code," i.e., the output from 0 to 9 is at L which corresponds to the counted pulse number.

2. Selector pulse form

The selection process is effected with two relay contacts. FIGS. 12a and 12b show the time pulse development of the selection process. When the pulse for a digit (FIG. 12a) ends, the working contact closes first, etc. After presetting time t_r of about 10 to 20ms, the resting contact nsi completes one to ten pulses of dura-

tion $t_o = 100$ ms, in each case depending on the digit, divided into an opening time $t_1 = 62$ ms and a closing time $t_2 = 38$ ms. The digit 0 indicates 10 pulses. On expiration of the last opening time t_1 for a digit, after a further time $t_3 = t_2 = 38$ ms, the nsi contact again drops. A pause of $t_p = 800$ ms (FIG. 12) then follows until the start of the selector pulse development for the next digit.

3. Number Register

- 10 The number register consists of a pin cassette with eighteen pins 7. These pins 7 are all of the same length and can be inserted in the cassette and preset to any of 13 different stages or teeth of the rack bar 4. Each stage represents a different digit or a switching order.
- 15 The pins are then scanned in succession, the length of the part of the pin projecting from the cassette indicating the value of the digit or the nature of the order. In addition to the digits, there are three switching or control orders:
- 20 Z — intermediate stop breaking the selection sequence after the preselector number has been run off;
- 25 P — interval, for extending the interval time between two digits by 800ms at each step;
- 25 B — end of number, shown in the cassette by $B =$ blind pin.

In the B position, the pin is completely contained in the cassette and serves only for lateral support. For this reason, the cassette must always be kept full, i.e., charged with 18 pins: e.g., if only 15 pins are required for a call number, three pins must be set to "blind," namely, the B position.

4. Switching Function

- 35 4.1. Cassette scanning and selector pulse formations (FIG. 14)
- For scanning, the programmed pin cassette is inserted in the cassette switch $S1$, see circuit diagram. The individual pins then move corresponding sliding contactors on the contact rails $13a$ identified in FIG. 14 from $A1$ up to $A18$, which according to the particular pin lengths projecting from the cassette form short circuits between a particular contactor rail $13a$ and any one of the thirteen contactor rails B (12a).

The B contactor rails (12a) for the digits 0 to 9 are connected through the gates $G1$ to $G10$ with the decoder circuit $DC3$ and flipflop $FF2$ with the counting decade $ZD3$; and the A contactor rails correspondingly through the diodes $D1$ to $D18$ (for reciprocally decoupling the decoder outlets) and the decoder circuits $DC1$ and $DC2$, with the two counting decades $ZD1$ and $ZD2$. In the resting state all three counting decades are zeroed, i.e., only the here unused zero outputs of the three decoder circuits are at level L .

55 To release the scanning function, the starting key $TA1$ (84) is depressed. This causes the output of gate $G31$ to reverse from H to L . This negative pulse flank causes the output of gate $G33$ also to reverse from H to L . At the same time, $G30$, the output of which is now at H -level, blocks any further action of the starting key during the selection sequence. This block can only be released by a Z or E control order, or by pressing the stop key $Ta2$ (83).

60 The lamp $La1$ is now connected through $G37$ and the transistor $Ta8$, indicating that the working function is now set.

The negative flank at the output of $G33$ forms the starting signal triggering the monostable flipflop $MF1$

through its input A1. The positive pulse at the output Q of MF1 is recorded in the counting register ZD1 and thereby sets the output 1 of the decoder DC1 to the L-level. This has now selected the first cassette pin.

In addition, the negative flank of the pulse, through Q/MF1 and G25 now triggers the monostable "interval flipflop" MF2.

The selection sequence for any digit is thus always preceded by an interval since recording in the counting register ZD1 or ZD2 always takes place at the beginning of an interval (FIG. 13). The interval t_p can be preset by means of the potentiometer P4.

After expiration of the interval time t_p , the flipflop FF3 is set, through the output Q whereof the nsa relay Re2 is activated, i.e., the nsa contact is closed. In addition, the monostable flipflop MF3 is triggered for the lead interval t_r , (FIG. 12). On expiration of the lead interval t_r the flipflop FF4 is set which through the transistor Ta3 releases the pulse generator with the transistors Ts1 and Ts2. The pulse generator now switches the nsi relay Rs1 in rhythm with the selection event (FIGS. 12a and 13), the contact opening time t_1 being adjustable by the potentiometer P1 and the contact closing time by the potentiometer P2.

Simultaneously, the positive synchro-pulses are recorded by the counting register ZD3, verifying through the decoder outputs 1 to 9 of DC3 and the output Q of FF2 the digit stored by the first cassette pin.

If, for instance, the first digit is 9, the contactor rail A1 and the contactor rail B11 are shorted. Since the output 1 of DC1 is at L, L is also at the top input of gate G9. At the negative flank of the ninth synchro-pulse, output 9 of DC3 is at L. Both inputs of G9 are at the L-level and, through G19, MF1 can be triggered at its input A1. MF1 determines the time $t_3 = 38ms$ which can be set by the potentiometer P3.

The positive flank of the pulse at the output Q of MF1 immediately restores the flipflop FF4 through G27 which again blocks the pulse generator. After a further 38ms, the negative flank of this pulse restores the flipflop FF3 through the gates G25 and G26, and G25 also triggers the interval mono-flipflop MP2. This again cancels the nsa-relay Rs2 and the next interval period begins (FIG. 12).

The negative pulse at the output $\bar{Q}$ of MF1 zeros the counting register ZD3 through the gate G21 and the flipflop FF2 is restored (if the latter is set by a digit 0).

Besides this, the pulse at Q/MF1 is again recorded in the counting register ZD1 and sets output z of the decoder DC1 to L-level. The second cassette pin and/or the contactor rail A2 have thus been selected and the corresponding events are repeated.

The flipflop circuit FF2 is used in the event that a cassette pin is scanned for the 0, i.e., 10 synchro-pulses are required. At the 10th synchro-pulse, the output Q of the flipflop FF2 is set to L by ZD3.

The contactor rails A1 to A9 and/or the cassette pins 1 to 9 are selected through ZD1 and DC1, while the contactor rails A10 and A18 and/or cassette pins 10 to 18 are selected by ZD2 and DC2. The transfer from the counting register ZD1 to ZD2 is made as follows:

If the contactor rail A9 has been selected, the L level at the output 9 of DC1 now releases the counting register ZD2, hitherto blocked and zeroed through its input R_{01} , so that now the next and simultaneously 10th pulse from Q/MF1 is recorded in both counting registers (ZD1 and ZD2). ZD1 and DC1 are again zeroed and

output 1 of DC2 goes to L-level; i.e., contactor rail A10 is selected. Simultaneously, through G24 the flipflop FF1 is prepared to be reversed by the 10th pulse of Q/MF1. Now, the flipflop FF1, after this 10th pulse blocks the counting register ZD1 through gate G25 and its input R_{02} against all further counting pulses and allows the counting register ZD2 to receive further counting pulses through an L-level at its input R_{02} .

4.2. Cancelling Procedure

10 After scanning of the last cassette pin in position A18, the following counting pulse from Q/MF1 similarly zeroes the counting register ZD2. The resulting negative pulse flank at output D of ZD2 is passed through the capacitance C9 to the input of the gate G28 and initiates the cancelling procedure. If fewer than 18 pins are required for a call number, the L-level of the control order B (= end of number) initiates cancelling procedure at another input of G28. The contactor rail B13 now carries the L-level of a B-control order 15 when one of the blind pins in the cassette is scanned.

Similarly, cancelling procedure can be initiated through a third input of the gate G28 by depressing the stop key Ta2.

The fourth input of the gate G26 is coupled with an 20 RC link (R43/C10) which, when the appliance is switched on or should the mains voltage fail, initiates cancelling procedure and returns the electronic system to the resting position.

In the cancelling procedure itself, the output of the 25 gate G29 goes (on the shorting side) from H to L-level. This L-level signal on the cancelling line releases the following functions:

A. The gates G33 and G34 are reset (these gates are switches as a so-called RS-flipflop);

B. The H-level applied to the output of G34 now sharply curtails any interval period presently running, through the gate G38 and the two transistors Ts6 and Ts7 and immediately on termination of this abbreviated interval period, through G30, cancels the blocking of 30 the starting key;

C. The lamp La1 is again extinguished through the reset gate G33;

D. The L-level at the output of G34 restores the two 35 flipflop circuits FF3 and FF4 through gates G39, G26 and G27 and blocks them in this condition. This inhibits the effect of a still-persisting interval period or a persisting selection event. In addition, shorting-side relay responses when switching in the mains supply or failure thereof are prevented. This block can be removed only by depressing the starting key;

E. The counting registers ZD1 and ZD2 are zeroed and the flipflop FF1 restored;

F. The coupling register ZD3 is zeroed through gates 40 G21 and G22 and the flipflop FF2 rests.

The electronic system is now again in the resting position and a new scanning cycle initiated by the starting key 84.

When the cancelling procedure has been initiated by 45 depressing the starting key 84, the simultaneously actuated Gu-contact (cradle interruptor contact) through which a nsi-conductor is led, briefly interrupts the subscriber loop, allowing repeated selection without first having to lay down the handset of the telephone instrument.

4.3. Intermediate Hold

A control order Z = hold, for interrupting selection procedure after preselection, produced by applying an

L-level to the contactor rail 82, occurs at the beginning of every interval period. This abbreviates the interval time through the gate G38 and the transistors Ts6 and Ts7 and on termination of this abbreviated interval period passes through G35 and G36 as a negative resetting pulse at G33 and G34. This again releases the starting key 84 through G30 when, through G34, G39, G26 and G27, the two flipflops FF3 and FF4 are held in the reset position (cf. cancellation procedure, point d).

The selection procedure is thus arrested. Through the second input of G37, the Z-order maintains the lamp La1 in circuit. The selection procedure is resumed by depressing the starting key 84.

4.4. Interval Extension

The control order P = interval is used to lengthen or extend the interval time by a further 800ms (actually, by $t_p + t_3 = 838\text{ms}$), i.e., to double the interval time between two digits by repeating the interval period. It appears as an L-level on contact rails B1 at the beginning of each successive interval period. Through G40 and diode D23, it opens diode D22 so that at the end of this interval period, with the negative flank of the pulse at the output Q of MF2, the monostable flipflop MF1 is immediately triggered again through D22 and G41 and thereby, after the time interval $t_3 = 38\text{ms}$, through G25, the interval flipflop MF is triggered once more, i.e., the interval period is repeated.

Through the second input of G39, the P order holds the two flipflop circuits FF3 and FF4 in the reset state to prevent the initiation of selection procedure after termination of the first interval period. At the beginning of the second interval period, the next digit pin is preselected through MF1, so that the block on FF3 and FF4 is omitted and on termination of this second interval period, the selection procedure for this number pin can be resumed.

It is also possible to insert a number of interval pins side by side. The interval time is then extended in each case by 838ms.

5. Mains Component

The mains component comprises a mains transformer Tr1 and a rectifier unit as well as a stabilizing circuit with the transistors Ts 9, 10, 11 and 12 for the 5-volt working current, adjustable by the potentiometer P5.

Should a fault appear in the stabilizing circuit, the Zener power diode (breakdown diode) D25 prevents the output potential from rising above 6 volts and thereupon melts the safety fuse Si3.

The 12-volt working current for the relays and the lamp is tapped directly from the charging capacitor C16. Since the two relays Rs1 and Rs2 have very short response times (about 1ms), the deviations of the 12-volt working tension due to the usual fluctuations in the main supply current remain practically without influence on the selector pulse form.

Important features of the invention influencing the reliability in operation and manufacturing economy of the appliance result further from the design embodiment of the sliding contactor element, the contact magazine and the cassette holder. In this regard, refer to the partially modified form of embodiment represented by FIGS. 20 to 24.

A material feature in this regard is that the slide 8 effecting the resetting of all the sliding contactors 10 together with the pins 6 which act as stop elements for the motion of the cassette 17, are located on the inte-

gral cassette holder 3 which is guided in the half-open lateral guides 18 of the slider guide rail 19 integral with the casing.

This arrangement of the pins 6 and the slide 8 with reference to the slide guide 19 ensures with a minimum expenditure of manufacturing means and effort that the sliding contacts are always correctly arranged in their starting position and the distance of the end faces of the pins 7 from the corresponding end faces of the sliding contacts 10 in the starting position of the cassette 17 and the said sliding contacts 10 is always the same so that errors in selection are thereby entirely excluded.

The same purpose is served in this embodiment of the invention by providing the cassette holder 3 with a plane surface 20 for the reception of the cassette 17.

These arrangements prevent skewing of the cassette in action and provide positional locking thereof in the starting and working positions.

A further important feature is that the lower part of the contact store has a stop rail 21 parallel with the slide 8 against which the sliding contacts 10 are correctly aligned in their starting positions with their studs 9 pressed by the slide 8.

This arrangement serves the purpose of easy control, high reliability in operation and inexpensive manufacture. The stop rail ensures that the sliding contacts are always correctly aligned in a constantly maintained starting position. Since the length of stroke of the sliding contacts are assigned them by the pins 7 is a measure of correct number selection, this form of alignment is of great importance.

A further, very important feature is that the sliding contacts 10 have on their ends opposite to their studs 9 guiding noses 22 working in guides 23 on the upper side of the contactor and thereby aligning the sliding contacts 10 parallel with each other in the correct starting position.

This ensures that the sliding contacts cannot in any circumstances become even slightly skewed; they are always in alignment parallel with each other. The appliance consequently always operates correctly even under extremely severe operating conditions, i.e., in the presence of shocks or vibration or in oblique attitudes.

FIGS. 20 to 24 further show the following additional safeguards: FIG. 20 shows a cassette holder 3 carrying a cassette 30. Two pairs of parallel, lateral guide rollers 31 are also shown, which support the cassette holder 3 laterally. In addition, the front end of the cassette holder 3 carries lateral guiding studs 32 for guiding the cassette 30.

FIG. 21 shows next these guide rollers 31 and guiding studs 32 a toggle switch 33 which is tripped by the forward edge 34 of the cassette holder 3 in its end position. This toggle switch closes in this position and thus allows initiation of the scanning procedure.

An additional mechanical interlock is shown in FIG. 21 in the form of a ball-shaped pawl 36 held by a spring 35 against the cassette holder 3. In the position shown in FIG. 21, this ball locks in a notch in the cassette holder 3 and thus additionally acts as a terminal lock.

FIG. 22 shows the lower part or base of the contact store in a slightly different arrangement from what is shown in FIGS. 15 and 16. In this case, an additional crossbar 37 is fitted as a stop for the studs 9 of the sliding contacts 10 (cf. FIG. 17).

FIG. 23 shows the upper part or cap of this contact store, according to which the upper side of the cap is equipped with a leaf spring 38. This spring blade 38 is formed of a plurality of reciprocally parallel spring teeth or tongues.

FIG. 24 shows similarly that these spring teeth 39 can by means of a pressure pin 40 and a locking ball 41 engage with notches 42 in a rack bar on the sliding contacts 10.

FIG. 25 shows a top view of the appliance with a total of 50 subscriber keys 101. When any one of these subscriber keys is depressed, a contact on a contactor rail 102 (FIG. 26) is closed whereby one particular digit of the preset call number sequence is selected.

These call number sequences are stored on pins 103 of which groups of eighteen each are arranged in a notch above one another (cf. also FIG. 26). These pins can be inserted to different depths in a guide plate 104, as will presently be explained in more detail. In the particular form of embodiment represented, two such guide plates are arranged to the right and left of the appliance, with two corresponding sets of notches and rows of pins. Each guide plate carries 25 preset call numbers with a maximum of eighteen digits each.

A fully-withdrawn pin 103 is shown on the top left of FIG. 25. Below, a fully inserted pin is shown which is thus in the resting or idle position.

FIGS. 25 and 26 further show a speaking key 105, a sound-volume control 106, a loudspeaker aperture 107, a switch 108 for running off the call numbers and locking means 109 for the contact rails.

FIGS. 27 and 28 show details of the arrangement with the contact pins 103 and guide plates 104. This indicates that the contact pins have marks 1 to 0 as well as additional markings P/Z, each of which corresponds to a particular current-pulse train. The upper side of the pins is provided, in accordance with this number sequence, with a toothed rack bar 110 between the teeth whereof plastics tongues 111 extrusion-moulded on the guide plate 104 are caused to enter.

These figures further show that each guide plate 104 has for each pin a separate receiving slot 112.

At the front end, these pins have a hammer-head expansion 113 with a stop pin 114.

At the rear end the pins 103 have slots 115 on the end face which are also more clearly shown in FIG. 29. Each slot accommodates a forked spring 116 having at its front end two cups 117 acting as contact studs and further equipped with transversely fixed check pins 118. The forked springs end in shorter legs 119.

The contact ends of the forked springs coact with conductor plates 120 in particular so that each motion path or slide track of each pin is delimited respectively by two conductor plates. In this exemplary form of embodiment, each conductor plate has 13 transverse contact points 121 and eighteen longitudinal contact points 122.

The pins 103 on the left in FIG. 27 are shown in the resting or starting position and the right-hand pin is fully withdrawn. P indicates an interval and Z an intermediate hold. The numbers 1 to 0 correspond with the selection numbers on the dial of a telephone or teleprinter.

Thus, each such pin controls both the ratchet engagement and the operation of the contact points. Erroneous selections are thus excluded as far as possible. Both

programming and structural assembly are simple and reliable.

The exemplary form of embodiment described above is in no way restrictive for the object of the present invention. Thus, the "cassettes" may be replaced by any other form of preset or programmed switching elements. An important feature is that these switching elements can be preselected or preset by the actual user or operator. Operation by a starting key is also not a prescriptive feature. Starting can also be performed externally by signal. In addition, other pulse-signal trains or sequences than the numerical sequence from 1 to 0 in telephone operation can be emitted.

By way of example of the manner in which the device according to the invention operates, reference may be added to FIG. 24 when the cassette holder 3 is pulled out of the casing of the device, the rail 8 on the cassette holder engages all of the lugs 9 on the sliders 10 and pulls the sliders 10 back to a starting point and wherein lugs 9 abut stationary rails 37 in the casing.

A cassette is prepared by adjusting the pins 7 to respective positions therein, whereupon the cassette cover is replaced and this locks the pins 7 in their adjusted positions in the cassette.

When the cassette is then placed on the cassette holder it is fixed to the holder by the pins 6 on the holder which engage apertures 5 in the cassette. When the cassette holder is then pushed into the device the pins 7 will engage respective ones of sliders 10 and move the sliders axially in conformity with the setting of the respective pins. As the sliders are adjusted the bridging contact spring on the end of each slides over the arrays of contact strips, one set of which is parallel to the direction of adjustment of the sliders and the other set of which extends at right angles thereto.

In each adjusted position of each slider except for the rest position thereof, the bridging contact spring will bridge between a pair of contact strips, one of each array, and thereby carry out switching operations.

A preset cassette is not the only device that can be employed for adjusting the sliders and it is conceivable, as in the modification of FIGS. 25 and 26, to preset the sliders in each of a plurality of rows thereof and then to control the selection of the rows by the manipulation of keys 101 provided on the device.

Modifications may be made within the purview of the appended claims.

What is claimed is:

1. A pulse emitting device especially adapted for use in telephone and teleprinter systems and the like and operable for emitting pulses for transport in the system; said device comprising a casing, a plurality of switches in said casing, switch control elements adapted for co-operation with said switches and adjustable in said casing, scanning means in the casing connected to said switches and operable to scan the switches sequentially, a control device insertable into operative position in said casing and including adjustable members operable to cooperate with said control elements to position said control elements relative to said switches upon insertion of said control device into said casing, pulse generating means connected to and under the control of said scanning means and operable for generating pulses in conformity with the positions of said control elements relative to said switches, and means for initiating operation of said scanning means when

said control device is inserted into operative position in said casing.

2. A pulse emitting device according to claim 1 in which said control device comprises a cassette, and said adjustable members comprise pins adjustably mounted in said cassette.

3. A pulse emitting device according to claim 2 in which each pin has one adjusted position in the respective cassette in which it does not move the respective control element into switching position.

4. A pulse emitting device according to claim 2 in which each pin has one adjusted position in the respective cassette in which the interval between successive pulses generated by said pulse generating means is modified.

5. A pulse emitting device according to claim 2 in which each pin has an adjusted position in the respective cassette in which a pulse sequence being generated by said pulse generating means is interrupted.

6. A pulse emitting device according to claim 5 which includes means for resuming said pulse sequence following said interruption thereof.

7. A pulse emitting device according to claim 2 which includes a slider pertaining to each control element, each slider at one end being engageable with the end of the respective pin, a contact spring on the end of each slider remote from the pin end thereof operable to cooperate with said switches to perform switching operations in the adjusted positions of said slider when said cassette is in operative position in said casing.

8. A pulse emitting device according to claim 2 in which said switches comprise parallel spaced opposed arrays of contact strips mounted in said casing with one array extending in the direction of insertion of said cassette and the other array extending angularly thereto, a slider in the casing pertaining to each pin and adjusted in conformity with the adjusted position of the pin when the cassette is inserted into said casing, and a forked contact spring on each slider adapted to engage a respective contact strip in each said array in adjusted positions of said slider.

9. A pulse emitting device according to claim 2 which includes cooperating elements of detent means on said pins and said cassette to retain said pins in predetermined adjusted positions in said cassette.

10. A pulse emitting device according to claim 9 in which said cassette comprises upper and lower portions slidably engageable with each other.

11. A pulse emitting device according to claim 7 in which each slider includes a stud projecting therefrom, and means for engaging said studs to return all of said sliders to an end position thereof.

12. A pulse emitting device according to claim 11 which includes a cassette holder reciprocable in said casing, and including pin elements for engaging holes in said cassette to lock the cassette to the holder.

13. A pulse emitting device according to claim 12 in which said means for engaging said studs is connected to said cassette holder whereby the withdrawing of said cassette holder from the casing resets all of said sliders, said casing including guide means for guiding said holder therein during the insertion and withdrawal of said cassette.

14. A pulse emitting device according to claim 12 in which said cassette holder has a planar support surface for receiving said cassette.

15. A pulse emitting device according to claim 13 in which said casing includes a stop bar engageable with said lugs on the opposite side of said means for resetting said sliders when the cassette holder is withdrawn from said casing.

16. A pulse emitting device according to claim 15 in which said casing comprises upper and lower members between which said sliders are disposed, said members having groove means therein in which said sliders are 10 slidable.

17. A pulse emitting device according to claim 12 in which said casing includes guide bars on opposite sides of said cassette holder for guiding said cassette holder in sliding movement in said casing.

18. A pulse emitting device according to claim 12 in which said cassette holder has guides at the sides thereof for engaging the sides of a cassette mounted thereon.

19. A pulse emitting device according to claim 1 20 which include interlock means in said casing actuated in response to insertion of said control device into operative position in said casing for making the pulse emitting device effective.

20. A pulse emitting device according to claim 19 in 25 which said interlock means includes a switch mounted in the casing.

21. A pulse emitting device according to claim 1 which includes detent means in the casing engaging said control device and operable for releasably retaining the control device in operative position in the casing.

22. A pulse emitting device according to claim 7 which includes means for insuring that the contact springs on the sliders operatively cooperate with said switches in adjusted positions of the sliders.

23. A pulse emitting device according to claim 7 which includes cooperating elements of detent means on said casing and sliders for releasably locating said sliders in adjusted positions thereof.

40 24. A pulse emitting device according to claim 23 in which said detent means includes leaf spring means in the casing having a spring blade pertaining to each slider.

45 25. A pulse emitting device according to claim 23 in which said detent means comprises recesses formed on each slider, an element in the casing engaging the recessed side of each slider, and spring means in the casing acting on said elements.

50 26. A pulse emitting device according to claim 7 in which each slider has a forked shaped spring on one end thereof, each forked shaped spring having contact points thereon cooperating with said switches in each adjusted position of the respective slider.

55 27. A pulse emitting device according to claim 26 in which each spring is bifurcated and each said slider has apertures therein, the arms of each spring having bosses formed thereon extending through said apertures and forming contact points.

60 28. A pulse emitting device according to claim 27 in which each boss on each arm of said contact spring comprises parallel sides and a rounded outer end.

29. A pulse emitting device according to claim 28 which includes pins extending transverse to said sliders and fitted in the rounded outer ends of said bosses on the arms of said contact spring.

65 30. A pulse emitting device according to claim 29 in which each of said bosses has a short leg projecting

therefrom on the side opposite the main portion of the respective contact spring.

31. A pulse emitting device according to claim 30 in which each slider has a recess extending into said one end thereof forming a socket in which the respective contact spring is mounted.

32. A pulse emitting device according to claim 26 in which said casing includes a guide plate, columns and rows of guide apertures in said guide plate, a respective slider in each said guide aperture, and cooperating elements of detent means on each slider and said guide plate.

33. A pulse emitting device according to claim 32 which includes conductor plate means with transverse and longitudinal contact regions thereon pertaining to each column of sliders.

34. A pulse emitting device according to claim 33 in which each slider at the end thereof opposite the contact spring comprises means for actuation of the respective slider in the direction of the length thereof.

35. A pulse emitting device according to claim 34 which includes a plurality of said guide plates mounted in a cassette, said cassette having slidable side walls.
